COMBINED BALL POINT PEN AND MULTIPLIER

Louis Bodor, 1220 Fillmore St., Hollywood, Fla.

Filed Feb. 29, 1960, Ser. No. 59,546

Term of patent 3½ years

(Cl. D74—17)

FIG. 1 is a front elevational view of a combined ball point pen and multiplier showing my new design.

FIG. 2 is a rear elevational view thereof.

FIG. 3 is a top plan view thereof.

I claim:

The ornamental design for a combined ball point pen and multiplier, as shown.
